Inventor.

United States Patent Office.

ELI HUNT, OF SHELBURN, INDIANA.

Letters Patent No. 71,760, dated December 3, 1867.

IMPROVED WASHING-MACHINE.

The Schedule referred to in these Letters Patent and making part of the same.

TO ALL WHOM IT MAY CONCERN:

Be it known that I, ELI HUNT, of Shelburn, in the county of Sullivan, and State of Indiana, have invented a new and improved Clothes-Washing Machine; and I do hereby declare that the following is a full, clear, and exact description thereof, which will enable others skilled in the art to make and use the same, reference being had to the accompanying drawings, and to the letters of reference marked thereon.

This invention relates to a new and improved clothes-washing machine, of that class which is provided with a rotary clothes-receptacle. The invention consists in placing a rotary clothes-receptacle having a periphery composed of slats and provided internally with lifters, the clothes-receptacle being placed within a suitable suds-box, and all arranged in such a manner that the clothes, as the receptacle is rotated, will be passed through the suds, raised or lifted out therefrom, and allowed to drop from the top of the receptacle into the suds, to be again passed through it, which operation effectually cleanses the clothes. In the accompanying sheet of drawings—

Figure 1 is a transverse vertical section of my invention, taken in the line *x x*, fig. 2.

Figure 2, a front elevation of the same.

Similar letters of reference indicate like parts.

A represents a suds-box, which is of cylindrical form, and supported at a suitable height by any proper framing, *B*. This suds-box is provided with a hinged section, *a*, which serves as a lid or cover, and within the suds-box there is placed a cylindrical rotating clothes-receptacle, *C*, the shaft *b* of which has its bearings in the ends of the suds-box. The clothes-receptacle is composed of two circular heads, *c c*, and a periphery of rounds or slats, *d*, which admit of the suds entering it. It is also provided with a hinged section, *e*, to serve as a door to admit of clothes being placed in and taken from it. (See fig. 1.) Within the clothes-receptacle, to the inner sides of the rounds or slats, there are attached projections, *f*, which may be termed lifters, as they catch under the clothes and raise them out of the suds as the receptacle *C* rotates, the clothes dropping from them as they reach a position directly over the shaft of the receptacle. Any number of these lifters may be used, but three, placed on three rounds which are equidistant from each other, will probably be sufficient.

The suds-box is supplied with a requisite quantity of suds, the clothes to be washed or cleansed placed within the receptacle *C*, and the latter rotated by means of a crank, *g*, on one end of the shaft *b*. The clothes by the rotation of *C* are passed through the suds, raised upward and out from it by the lifters *f*, and drop therefrom into the suds as the lifters reach a point directly over shaft *b*. The clothes, in consequence of being subjected to this operation, are effectually cleansed, and without being injured in the least.

Having thus described my invention, I claim as new, and desire to secure by Letters Patent—

An improved clothes-washing machine, consisting of the open cylindrical clothes-receptacle *C*, provided with the lifters *f* and rods *d*, fitted within the cylindrical suds-box *A*, the hinged doors in the hinged top of the suds-box, and cylinder, all constructed, arranged, and combined to operate as described and specified.

The above specification of my invention signed by me, this 9th day of September, 1867.

ELI HUNT.
